Inventor.

UNITED STATES PATENT OFFICE.

EUGENE PRINGLE, OF GLOVERSVILLE, NEW YORK.

SEPARABLE BUTTON.

SPECIFICATION forming part of Letters Patent No. 391,076, dated October 16, 1888.

Application filed March 20, 1888. Serial No. 267,865. (No model.)

To all whom it may concern:

Be it known that I, EUGENE PRINGLE, a citizen of the United States, residing at Gloversville, in the county of Fulton and State of New York, have invented certain new and useful Improvements in Separable Buttons, of which the following is a specification.

My invention relates to separable buttons; and it consists of the parts, devices, and elements and combinations of parts, devices, and elements hereinafter particularly described, and specifically set forth in the claims.

The objects of my improvements are to produce a button-head which will have the stud-engaging part contained in the lower side half of the head, while the fastening-eyelet will form a part of the upper side half, so that the part of engagement of the coacting stud will be relatively below the lower half of the button-head, and also to provide in a stud an elastic holding-piece which will have engagement with the coacting button-head at a point relatively below the portion of the button-head above the material, while the body of the stud, instead of the elastic holding-piece, will itself sustain the pull, and, further, to provide specific means by which my improvements can be carried into effect in a separable button. I attain these objects by the means illustrated in the accompanying drawings, forming a part of this specification, in which—

Figure 1 is a sectional elevation of a button head and stud, both secured to the material and embodying the improvements in this invention. Fig. 2 is a sectional view of the button-head, showing a modified form of stud-holding piece. Fig. 3 is a sectional view of the fastening-eyelet piece. Fig. 4 is a view of the upper side clamping-piece, which contains the tube portion of the fastening-eyelet. Fig. 5 is a sectional view of the lower side clamping-piece. Fig. 6 is a sectional view of the stud-engaging piece shown to be employed in the heads illustrated in Figs. 2 and 11 and adapted to be clinched on the lower side clamping-piece. Fig. 7 is a sectional view of the stud-engaging piece having the lower side clamping-piece clinched on it. Fig. 8 is a sectional view of a stud-engaging piece, a lower side clamping-piece, and an eyelet turning piece secured together for use as shown in Fig. 1. Fig. 9 is a view of the same pieces

shown in Fig. 8, and showing a modified manner of securing the same together. Fig. 10 is a sectional view of the same pieces, showing the stud-engaging piece to have a modified form of engaging portion. Fig. 11 is a sectional view of a button-head having some of its parts modified in form of construction and relative arrangement. Fig. 12 is a sectional view of my improved stud for co-operation with the button-head. Fig. 13 is a plan view, from above, of the stud, illustrating the slitting of its base. Fig. 14 is a plan view of the same, showing another form of slitting. Fig. 15 is a side elevation of the stud. Fig. 16 is a transverse side elevation of the same. Fig. 17 is a plan view of a piece which can be used to hold the spring catch in the stud. Fig. 18 is a sectional view of the same, and Fig. 19 is a sectional elevation of the stud embodying spring-catch-holding piece.

The same letters of reference refer to like parts throughout the several views.

In the drawings, A represents the upper side or top shell of the button-head. B is the upper side clamping-piece secured with said top shell, and C is the fastening-eyelet secured within the upper shell and having its tube portion c held within the upper side clamping-piece.

D, Figs. 1, 2, 5, 7, 8, 9, 10, and 11, is the lower side clamping-piece, having a central perforation, d, and the upturned annular flange d'.

E, Figs. 2, 6, 7, and 11, is the stud-engaging piece, having the stud-receiving opening e and the annular stud-engaging surface e', which is beveled inwardly and downwardly, as shown in Fig. 6, so as to hold with the engaging parts of the stud after its passage through said opening.

In Figs. 1, 8, and 9 is shown piece E', which, with piece E², forms the equivalent to piece E, the central perforations, e² e', in said pieces forming the opening for the passage of the stud, as does perforation e in piece E, while the engaging rim e' operates as does the engaging rim e in the said piece E.

In Figs. 1 and 8 the outer flange-rim, d², of the under side clamping-piece, D, is shown to be clinched on the lower side of piece E', with piece E² between, while in Figs. 9 and 10 the reverse is shown. In Fig. 10 the edge margin

of engaging-rim e^4 is shown to be turned on itself, so as to produce a smooth rounded stud-engaging rim at the stud-receiving opening.

F, Figs. 1, 12, 13, 14, 15, and 16, is the post 5 of the stud S, and F' is the base of the said post. This stud-post F and its base are shown to be slotted from the lower side of said base to a short distance below the upper end of the post by one or more slits, f, as shown, and after being slotted the ring-form engaging piece G is placed within the upper portion of the slit of the post F, when the portion of the post at the base F' will be contracted, so as to substantially close the slit f and form the holding-groove f', as shown in Figs. 12, 15, and 16.

H, Figs. 1 and 12, is the stud-base-binding plate, provided with a central opening, h, through which the stud-post will readily pass, and I is a flanged fastening-eyelet, which is secured to the binding-plate H by clinching of the flange-rim h' on the outer edge portion of the flange i of the eyelet, with the parts of the slotted base F' between. This flange of the said eyelet I forms the upper side clinching-piece of the stud, while plate J forms the under side clamping-piece and is held secure with the material and stud by the tube portion i' of the eyelet passing through the central perforation, j, of said plate J and clinching on the edge portion of the same.

In this improved separable button the ring-form engaging-piece G is made to be elastic, and it operates to hold with the engaging-rim e^4 , or its described equivalent rim e^4 , to hold 35 the button-head from accidentally parting from the stud, while the lateral direction of strain of the pull on the stud will cause the latter to be so drawn toward the sides of the stud-receiving opening e^4 , or its described equivalent e^4 , as to cause the post to sustain the strain 40 instead of the elastic ring-catching piece G, which is shown to be arranged within the post in direction of its length, and so that this ring-form piece will receive the strain on two points 45 outside the stud.

By the above-described improvements I am enabled to cheaply produce a separable button which will be durable and strong in the fastenings of its parts to the material and in 50 their connection with each other.

In some cases, if preferred, the contraction of the base of the stud below the engaging-piece G (shown in Figs. 12, 15, and 16) can be omitted, and the said engaging-piece can 55 be supported in place within the slit in the post by the central boss, l, made central with the disk l' of plate L. (Shown in Figs. 17, 18, and 19.) This can be readily effected by placing the piece L against the slotted base of the 60 stud-post, with the central boss, l, within the central base of the same and against the lower

side of the piece G, as shown in Fig. 19, and then securing this plate L with said base by any suitable binding-piece; or, if preferred, a strip, L', Figs. 20 and 21, having a central projection, l'', can be placed in the slit in the base F and lower portion of the stud-post to effect the same result.

Having described my invention, what I claim, and desire to secure by Letters Patent, is—

1. In a button-head of a separable button, the combination, with the eyelet-fastener in the upper side portion of the button-head, of the stud-engaging piece E, having a central stud-receiving opening, e , or its described equivalent, and an annular stud-engaging rim, e' , at the lower side of said opening, and the under side clamping-piece, D, secured to said stud-engaging piece and coacting with the said eyelet-fastener, substantially as and for the purposes set forth.

2. In a separable button, the stud formed by the combination of the slotted stud-post F and the elastic ring-form engaging piece G, arranged in said post in direction of its length 85 for operation with an engaging-piece in the button-head, substantially as and for the purposes set forth.

3. In a separable button-head, the stud-holding piece E, having the internal sloping 90 tubular portion, e' , for engagement with a stud, and having also the outer clinch-turning surface, and an under side clamping-piece, D, for co-operation with a fastening-eyelet, substantially as and for the purposes set forth.

4. In a button-head of a separable button, the combination, with the lower side clamping-piece, D, secured to the upper side clamping-piece, B, by an eyelet, of the stud-engaging piece E, having the downwardly and inwardly inclined annular engaging-surface e' , for holding with an elastic holding portion of a co-acting stud, substantially as and for the purposes set forth.

5. In a separable button, the stud S, having its base and post slotted upwardly to within a short distance of the top of the post, and the base-binding plate secured to a fastening-eyelet and clamping on the slotted base of the said stud, and a lower side clamping-piece 110 having the tube of the eyelet clinched therewith, of the ring-form engaging-piece contained within a longitudinal slit in the stud post and a coacting stud-engaging piece secured to the lower side of a button-head when it is secured 115 to the material, substantially as and for the purposes set forth.

EUGENE PRINGLE.
